UNITED STATES PATENT OFFICE.

CHARLES M. STEIN, OF PARIS, FRANCE, ASSIGNOR TO SOCIETE ANONYME DES APPAREILS DE MANUTENTION ET FOURLS STEIN, OF PARIS, FRANCE, A CORPORATION OF FRANCE.

TUNNEL FURNACE.

Application filed August 19, 1921. Serial No. 493,599.

To all whom it may concern:

Be it known that I, CHARLES M. STEIN, a citizen of France, residing at Paris, France, have invented a certain new and useful Tunnel Furnace, of which the following is a specification.

The invention relates to furnaces of the type wherein the material to be heated, for example steel, brass, brick, etc., is moved progressively through the furnace structure.

One object is to provide a furnace wherein the heat contained in the heated material (after the latter has reached the desired temperature), is utilized efficiently to preheat the air supply, thus avoiding the necessity of employing regenerators or recuperators, in the ordinary meanings of the terms, in connection with the furnace.

Preferably the air is led through the preheating chamber in such manner as to prolong its contact with the heated material and insure that only properly preheated air is withdrawn therefrom for combustion purposes; and the gases of combustion are led through and withdrawn from the heating chamber so as to bring about thorough contact with the material to be heated, and withdraw only such gases as have given up a maximum amount of their heat.

Another object is to construct the furnace in such manner that the air supply will be under proper control, both as regards quantity and temperature.

Another object is to provide a furnace which by simple manipulations may be adjusted to operate with fuels of different quality.

Further objects and advantages of the invention will be in part obvious and in part specifically pointed out in the description hereinafter contained which, taken in connection with the accompanying drawings, discloses a preferred embodiment thereof; such embodiment, however, is to be considered merely as illustrative of its principle. In the drawings:

Fig. 1 is a vertical longitudinal sectional view of a tunnel furnace made in accordance with the invention.

Fig. 2 is a transverse section of the preheating chamber, taken on line 2-2 of Fig. 1.

Fig. 3 is a transverse section of the heating chamber, taken on line 3-3 of Fig. 1.

Fig. 4 is a transverse section taken on

line 4-4 of Fig. 1, showing particularly the gas and air conduits employed in connection with the furnace.

Fig. 5 is a transverse sectional view showing the combustion chamber, taken on line 5-5 of Fig. 1.

The illustrated embodiment of the invention is designed particularly for use as an annealing furnace, and comprises an elongated heating chamber 1, having a roof 2, and side walls 3, which may be of ordinary construction, the bottom of the chamber being provided with rails 4 adapted to support cars 5 on to which the sheets to be annealed may be loaded, and the cars moved 70 successively into the heating chamber 1 through a door 6 located at its entrance end.

At the delivery end of the heating chamber 1 there is located a combustion chamber 7, in which a mixture of air and fuel is 75 ignited and the products of combustion passed through the heating chamber in a direction opposite to the direction of travel of the cars therethrough, and are intimately brought into contact with the material to 80 be heated to raise the temperature of the latter to the desired point.

In order to provide a supply of preheated air to the combustion chamber without necessitating the employment of a recuperator 85 or regenerator of ordinary form, the air which is to support combustion is led past the cars 5 after the material carried by the latter has been raised to the desired temperature. This step of preheating the air is 90 carried out in a preheating chamber 8 which conveniently may be placed end to end with the heating chamber 1, and the rails 4 are led through the preheating chamber 8, in such manner that the cars 5 may travel from the 95 delivery end of heating chamber 1 through a doorway 9 into the preheating chamber 8, and pass out through a door or the like 10 at the end of the preheating chamber.

The air which is to support combustion is 100 led into preheating chamber 8 through an intake passageway 11, and passes through the preheating chamber in a direction opposite to the direction of travel of the cars 5 therethrough, after which the air passes out 105 of the preheating chamber and is mixed with fuel to be burned in the combustion chamber 7. As shown in Fig. 1, I prefer to lead the cold air into the preheating chamber 8 adjacent the bottom of the chamber 110

- at its delivery end, and to withdraw the preheated air by means of one or more air conduits 13 located adjacent the upper portion of the entrance end of the preheating chamber, after which the air is led through suitable ports 14 (Figs 5) into combustion chamber 7. Thus the air to be preheated may stratify itself to some extent in the preheating chamber, and the heated air will rise 10 to the top of the chamber and pass out through conduits 13, whereas the air which has not been properly preheated will remain in further contact with cars 5 carrying the heated material minimizing the liability 15 of cool air passing from the intake passageway 11 out through conduits 13 without proper preheating.

In order to control the amount of air passing through the furnace, I prefer to introduce 20 the air through passageway 11 under pressure, from a blower 12 or the like, and dampers 15 (Fig. 5) are associated with the air conduits 13 to permit the rate of flow of the air to be adjusted. Thus the amount of 25 air fed to the furnace may be regulated as desired and also the speed at which it passes through the preheating chamber 8, whereby the desired temperature of the air may be obtained, as well as the desired quantity.

- 30 As shown in Fig. 4, it is preferred to employ two air conduits 13 issuing from opposite sides of the preheating chamber 8, thus balancing the flow of air through the preheating chamber to the combustion chamber 7. When the furnace is operating with lean 35 fuel such as producer gas, the gas may be lead in through intake gas conduits 16 (Fig. 4) connecting into ports 17 (Fig. 5) associated with the ports 14. The furnace, however, 40 may be readily shifted to operate with richer fuels such as coke oven gas or oil, by adjusting dampers 18 (Fig. 5) to close gas ports 17, and opening the supply pipes 19 which connect with fuel ports 20, adapted 45 to project the rich gas laterally into the combustion chamber above the material to be heated and in the path of the air issuing from the ports 14.

I prefer to locate the combustion chamber 7 at the upper portion of heating chamber 1, so that the flames may play downwardly over the material carried by the adjacent truck 5. A baffle 21 (Figs. 1 and 5) may also be employed, projecting downwardly from the top wall 2 of chamber 1 so as to confine the flames and insure that the products of combustion pass downwardly into thorough contact with the material to be heated instead of escaping along the 50 top portion of the combustion chamber. Further, I prefer to withdraw the products of combustion from the lower portion of the entrance end of heating chamber 1, as by one or more exhaust flues 22; only such 55 gases will sink to the bottom of the heating

chamber as have given up a maximum amount of their heat to the material carried by cars 5, thus the best efficiency of heat exchange is secured by leading the spent gases of combustion through and out of the 70 heating chamber in this manner.

In the operation of the furnace, communication between the preheating chamber 8 and the heating chamber 1 is first shut off by means of a removable door 22 interposed 75 between the same, the door being made as air-tight as possible in order to prevent a direct passage of air between the chambers without passing through the air conduits 13. The air is forced through the preheating 80 chamber 8 by the blower 12, and the quantity of air so fed may be controlled by adjustment of the blower. The cold air is directed through the intake passageway 11 into the lower portion of the preheating chamber at 85 its delivery end, and passes through the chamber into contact with the fully heated material carried by the cars 5 which are within the preheating chamber; as the air becomes preheated, it rises and is assisted 90 by natural draft in passing out through air conduits 13 to the combustion chamber; thus with the air conduits 13 located at the upper portion of the preheating chamber, it is insured that only properly preheated air 95 will be withdrawn from the chamber, and less air pressure is required to force the preheated air through conduits 13, and consequently the tendency of the air to leak past door 22 is decreased.

As appears from Figs. 2 and 3 the cross section of the preheating chamber 8 is preferably made larger than that of heating chamber 1 and thus the velocity of travel of the air through the preheating chamber is 105 less than that of the burned gases through the heating chamber. The time of contact in the preheating chamber between the air and the heated material therefore is relatively long, so that an efficient heat interchange may be effected, or, in other words, proper preheating of the air may be brought about without constructing a preheating chamber which is unduly long. The damper 15 shown in Fig. 5 may also be employed 115 to provide a further adjustment of the air velocity, and thus by means of the blower 12 and the damper both the quantity of air and its temperature may be varied to meet the conditions of operation of the furnace. 120

The mixture of air and fuel is ignited in the combustion chamber 7, and the flames pass downwardly into contact with the material carried, so that the adjacent truck 5 and baffle 21 serve to force the flames to pass 125 into close contact with such material. The burned gases then pass through heating chamber 1 into contact with the material carried by all the cars 5 contained within such chamber, and at the entrance end there- 130

of the coldest burned gases, which settle to the bottom of the chamber, are withdrawn through the exhaust flues 22.

When the material carried by the car 5 which is beneath the combustion chamber 7, is heated to the desired degree, the doors 6, 10 and 22 are opened and a new car pushed into the entrance end of heating chamber 1, thus advancing the car 5 which carries the 10 fully heated material from the delivery end of the heating chamber into the entrance end of the preheating chamber, and ejecting the car which previously was at the delivery end of the preheating chamber, and which 15 had given up as much heat as possible to the incoming air. The doors 6, 10 and 22 are then moved to closed position and the operation of the furnace is repeated as above described.

20 While a specific embodiment of the invention has been described, it is obvious that many changes may be made therein without departing from the spirit of the invention as defined in the following claims.

25 I claim:

1. The method of operating a tunnel furnace which comprises conducting a gaseous current, which is to enter into combustion, past the heated material to preheat the gaseous current, forming a combustible mixture including said gaseous current, igniting the mixture, and passing the products of combustion along the material to be heated at a relatively higher velocity than that at which 35 the gaseous current moves past the heated material.

2. The method of operating a tunnel furnace having an air preheating chamber and a heating chamber, which comprises moving the heated material from the heating chamber into the preheating chamber, passing substantially all the air required for combustion at a relatively low velocity through said preheating chamber, mixing the preheated air with fuel, igniting the mixture, and passing the products of combustion through the heating chamber at a relatively higher velocity.

3. The method of operating a tunnel furnace having an air preheating chamber and a heating chamber, which comprises moving the heated material from the heating chamber into the preheating chamber, passing air into the lower portion of said preheating chamber, and withdrawing the preheated air from the upper portion of said chamber, mixing the air with fuel, igniting the mixture adjacent the upper portion of the heating chamber, and withdrawing the same 60 from the lower portion of said heating chamber.

4. A tunnel furnace having an air preheating chamber and a heating chamber, removable means for shutting off communication between said chambers, and a conduit for preheating air leading from the upper portion of said preheating chamber to the upper portion of said heating chamber.

5. A tunnel furnace having an air preheating chamber and a heating chamber, removable means for shutting off communication between said chambers, means for forcing air under pressure into said preheating chamber, and a preheated air conduit extending between said preheating chamber 75 and the upper portion of said heating chamber.

6. A tunnel furnace having an air preheating chamber and a heating chamber, means whereby material to be heated may be 80 introduced into said heating chamber and withdrawn from said preheating chamber, an air intake passageway connected to said preheating chamber, and a waste gas flue leading from said heating chamber, said preheating chamber being of larger effective 85 cross section than said heating chamber.

7. A tunnel furnace having an air preheating chamber and a heating chamber, means whereby material to be heated may 90 be introduced into said heating chamber and withdrawn from said preheating chamber, means for forcing air under pressure into said preheating chamber, a conduit for preheated air leading from said preheating 95 chamber to said heating chamber, and a damper associated with said preheated air conduit.

8. A tunnel furnace having an air preheating chamber, preheated air conduits 100 leading from the upper portion of the preheating chamber on opposite sides thereof, a heating chamber having a combustion chamber adjacent the upper portion thereof, said air conduits leading to air ports in 105 said combustion chamber, and removable means for shutting off communication between said chambers.

9. A tunnel furnace, a heating chamber having a combustion chamber adjacent the upper portion thereof, an air preheating chamber, preheated air conduits leading from the upper portion of the preheating chamber on opposite sides thereof and connected to ports which open into said combustion chamber, and sets of rich and lean fuel ports associated respectively with said air ports.

In testimony that I claim the foregoing, I have hereunto set my hand this 12 day of July, 1921.

CHARLES M. STEIN.
